UNITED STATES PATENT OFFICE.

WILLIAM H. JORDAN, OF BROOKLYN, NEW YORK, AND GEORGE T. HANCHETT, OF HACKENSACK, NEW JERSEY, ASSIGNEES TO JORDAN AUTOMATIC SIGNAL COMPANY, OF NEW YORK, N. Y., A CORPORATION OF NEW YORK.

RAILWAY-SIGNAL.

No. 910,387.

Specification of Letters Patent.

Patented Jan. 19, 1909.

Original application filed June 14, 1905, Serial No. 265,209. Divided and this application filed May 31, 1907.

Serial No. 376,675.

To all whom it may concern:

Be it known that we, WILLIAM H. JORDAN, a citizen of the United States, residing in Brooklyn, county of Kings, and State of New York, and GEORGE T. HANCHETT, a citizen of the United States, residing in the town of Hackensack, county of Bergen, and State of New Jersey, have invented certain new and useful Improvements in Railway-Signals, of which the following is a description.

This is a division of an application for patent filed by us on June 14, 1905, Serial No. 265,209.

Our invention relates to that class of signals used upon electric railways which derive their power from the same source as that employed to propel the cars, but the invention may be applied to steam roads or to electric roads with the signals actuated by current other than that used to propel the cars.

The objects we have in view are, the production of means for actuating the semaphore in a danger or safety position as may be desired; the insuring that the different mechanisms will promptly respond to the signals; and the provision for actuating the signals irrespective of the voltage on the line.

We attain these objects by the mechanism illustrated in the accompanying drawings, in which—

Figure 1 is a view of a portion of the apparatus in use. Fig. 2 is a diagrammatical view of three stations, showing the circuits. Fig. 3 is a diagram showing the action of the actuating solenoids.

In all the views like parts are designated by the same reference characters.

The motive power of the device comprises two magnets or coils, preferably of the solenoid type, set opposite to each other and acting upon the same plunger or core. One of these magnets, when energized pulls the plunger in one direction, and the other pulls it in the opposite direction, the motion of the plunger being transmitted by appropriate means to a semaphore or other signal.

The box 11 carries the two actuating solenoids D and S in opposed relation and actuating a plunger A (see Fig. 2). In the particular embodiment of the invention illustrated, the solenoid D is designed to move

the plunger to actuate the signal 12 and move it to the danger position, the solenoid S acting in the opposite direction to move it to the safety position. Each solenoid is connected to the circuit in such a manner, as will be described, as to first energize the solenoid D, causing it to attract the plunger and move the signal to the danger position; upon the car passing the danger point, the circuit will be completed through the solenoid S, energizing it and retracting the plunger, causing the signal to move to the safety position. The boxes 11 are placed at suitable intervals, and the solenoids D and S are connected to circuit closers upon the trolley wire or at other points, as may be desired, in such a manner that each of the solenoids D will be first energized momentarily to cause the attraction of the plunger A just as the car is entering the danger zone, and at the proper point the solenoid S will be energized and the plunger retracted.

We have found in practice that solenoids which are properly wound to handle the high voltage of street railway practice, retain such an amount of residual magnetism that the opposing solenoid cannot attract the plunger against such residual magnetism during the short period of time which it is energized. We have provided means for eliminating this residual magnetism. Such means preferably comprises additional coils surrounding the main coils and adapted to be energized at the proper time. In Fig. 2 these coils are shown and designated by the characters D' and D''. The coil D' surrounds the coil S, and the coil D'' surrounds the coil D. These coils are preferably connected in series in such a manner that the coil D' will be energized simultaneously with the coil D, and the coil D'' will be energized simultaneously with the coil S.

Fig. 2 is illustrative of the manner of connecting a number of different signal stations; three are shown indicated by the characters 64, 65, and 66. The car will pass in the direction of the arrow, that is, from the right to the left. Upon reaching the contact shoe E' the current will pass along the wire W to the demagnetizing coil of the danger magnet of the station behind it (not shown) and through the main coil of the safety magnet of such station, setting the parts to the safety

position. The current will branch and pass through the demagnetizing coil D' of the station 64 and also through the main danger coil D at such station setting the parts to danger. They will remain in such position until the trolley comes in contact with the circuit closer E^3 . The current will then pass through the wire W , through the demagnetizing coil D^2 and through the safety coil S of the station 64, which will move the semaphore and target of such station to safety. At the same time the current will pass through the demagnetizing coil D' and danger coil D of the station 65 moving the parts to the danger position. The same action will be repeated when the trolley reaches the contact E^3 , the current passing over the wire W^3 and through the demagnetizing coil D^2 and safety coil S of the station 65 setting the parts to safety and at the same time will pass through the demagnetizing coil D' and danger coil D of the station 66 setting the parts of such station to danger.

We have found that in electric railway systems the electric pressure will vary widely, sometimes as much as fifty per cent., and in order that the magnets shall be operative at any of the pressures which may exist on the line they are so designed that at the lowest possible line pressure which is used their cores will always remain saturated. Under this condition it is evident that any higher pressure will produce no difference in the magnet action, and by this construction the signal is enabled to work reliably upon all of the pressures which are found in practice.

Fig. 3 illustrates a chart indicating the construction of the magnet. 67 represents abscissæ and 68 ordinates, the abscissæ representing difference of potential and the ordinates magnetism. The curve 69-70 represents the stages of magnetism resulting from certain pressures. This curve rises gradually up to a point of complete saturation, and then becomes nearly horizontal, as between the points 71 and 72. This line represents the point of complete saturation, anything below such line being the point of incomplete saturation. The ordinary form of magnet is adapted to be operative in stages of incomplete saturation, as between the points 73 and 71. At the point 73 there may be insufficient magnetism to actuate the moving parts of the semaphore.

By our invention we arrange the magnets to operate between the points 71 and 72, which will represent the greatest variations in pressure in the line. The points 71 and 72 represent points of complete saturation of the core, and consequently the magnet will operate with maximum power, even when energized by a minimum working current. On electric railway circuits the voltage varies very widely from about 250 to

550 volts. If the signaling magnet is so constructed that its core shall be saturated when its potential bobbins have a voltage of 250, their action magnetically will not be materially different when the voltage is 500. 70 It is true that the principal part of the curve which rates the flux and which in turn is a function of the magnetic pull is not quite parallel to the axis of the abscissæ, but it is nearly so, and if the magnet be designed 75 to be saturated at 250 volts, its magnetic action will be substantially the same as at all higher voltages. If on the other hand, as has been common heretofore, the magnet is designed so as to work when the rated 80 voltage of the line, 550 or 500 volts, as the case may be, is impressed upon it, then when 250 volts are on the line, the magnet not being saturated, will work on the steep part of the curve, between 73 and 71, and will 85 rapidly fall in flux to a much lower value, and is extremely likely to fail to operate. This is a very real trouble which we have encountered ourselves, and which has been encountered before, and which is obviated 90 by the device of designing the magnet so as to be saturated or nearly so at the time that the lowest potential ever found upon the line obtains. Absolute saturation and approximate saturation are impossible of specific definition, but for the purposes of illustration, the following table is appended. The lowest potential that obtains on the line will produce in the operative magnets the following flux values per square inch 100 with different materials:

Annealed wrought iron	100,000 lines	105
Soft cast iron	97,500 "	
Mitis iron	90,000 "	
Cast iron containing 6.5% aluminum	45,000 "	
Ordinary cast iron	40,000 "	

In designing electro-magnets for any purpose, it is customary to flux them at what is known as the working density of the magnetic metal. For cast iron this is about 40,000 lines to the square inch. For mild steel about 80,000 lines to the square inch, 115 and for soft Norway iron, about 90,000 lines to the square inch, and any attempt to flux these materials to higher values than these results in a very large expenditure of energy for a proportionately small additional magnetic result. For this reason, under ordinary designs, this is not resorted to, and any device containing over-saturated magnets would, under ordinary circumstances, be considered to be poor design and ill-advised. 125 We believe that the discovery of the fact that intense saturation was a desirable feature in the case of signal magnets working on varying voltages because thereby constancy of action was assured, is a very important 130

tant departure. Our own experience was, first, to make magnets for this work employing the set rules and regular working densities; we soon found that in greatly reduced voltage the magnets were inoperative. We then conceived the idea of enormously saturating the magnets and found that under these conditions the magnets operated substantially the same, no matter how the voltage varied. This was accomplished at the expense of extra power and additional copper in winding which ordinarily would not need to be employed, and was a departure from the set rules of designing magnets which in this case had peculiar beneficial application. We also observed that other designers were having similar troubles with their magnets and had not yet conceived the idea of over-saturating them to gain these ends. We therefore consider that this device is by no means obvious and cannot be reached except by experiment and research.

In designing an electric magnetic device of any kind, the designer is naturally led to produce a design which gives a maximum result with a minimum expenditure of electric energy and ordinarily over-saturation is considered a needless extravagance.

On page 87 of Thompson on *Magnetic Principles*, he states that it is not economical in B (magnetic saturation) beyond 16,000 lines to the square centimeter; in other words, he cautions the designer against extreme saturation,—which is the departure from the ordinary practice which this invention employs.

In electric railway work, the working voltage is supposed to be 500 to 550 and the dynamos supplying the power are constant potential or compound generators. An engineer, designing signals and having had experience in railway work, is apt to figure that the potential of the trolley line is 500 or 550 volts, and will forget the fact that many lines on which signals are necessary are fed by wires which are inadequate in capacity, and in which there is a large loss of voltage.

On page 345 of Thompson's work, before referred to, with reference to the "Design of magnets," he prescribes for magnetic cores 75,000 to 100,000 lines per square inch if of cast steel or wrought iron; 70,000 to 100,000 for making magnet yokes, if of cast steel or wrought iron; 35,000 to 50,000 if of cast iron. If a designer should follow these rules in constructing a magnet for the device in question, he would have a machine which would be very unreliable on moderate reductions of voltage and positively inoperative on great reductions of voltage, although it is conceded that the rules given by Thompson are the proper ones to follow under ordinary circumstances.

The following examples of electromagnetic apparatus containing electromagnets dependent for their current upon the magnitude of the line potential and designed in the usual way of fluxing at the normal working density to their detriment in operation, have come under our direct observation. The electromagnetic switch for the sectional conductor system on a 500 volts railway circuit and designed for Doty, McKnight, Grouton Co., which would operate at 500 volts but on lower potentials failed to be operative by reason of not bringing the magnet up to the saturation point at normal working voltage. Automatic cutouts in connection with signal lamps used on shipboard, made by the Fisher Electric Company and installed on board the boats of the Minnesota Steamship Company, adapted when a filament broke to open the circuit and ring a bell, gave continuous trouble by opening the circuit whenever the dynamo voltage happened to be reduced 15% or 20%, due to the fact that the magnets were not sufficiently over magnetized at normal voltage. Other cases are no doubt abundant.

By the statement "saturation" it is not intended to mean that absolute saturation is theoretically possible, that is to say, a point beyond which there would be absolutely no increase in magnetic lines for increase in current, but the intention to convey is, that a point can be reached practically so that to all intents and purposes the performance is the same as if absolute saturation were obtained. That is the common parlance in speaking of electromagnets, the absolute point for wrought iron being fixed at about 130,000 lines to the square inch.

It is quite true that Thompson states that it is the usual practice to design cores so that they can be utilized beyond the bend of the curve, but the point that he has reference to is immediately beyond the bend of the curve, so that a very small reduction in magnetizing power will drop the magnetism to the steep part of the curve where great reductions in magnetism will follow small reductions in current. By our invention, on the other hand, the magnets are raised to a point far beyond the bend of the curve so that a considerable reduction of current does not move the abscissa of magnetizing power far enough back toward the origin so that the ordinate is materially shortened. It may also be pointed out that to claim the impossibility of complete saturation is ultra-technical and comparable with the final value of current in a circuit. It is well known to mathematicians that the current in an electric circuit to which a certain electromotive force has been applied never reaches a final value but is continually increasing no matter how long said electromotive force may be applied. Practically,

however, it reaches such a value in a fraction of a second, so that any subsequent growth is insignificant, and 90 per cent. of practical electricians are not aware that there is any subsequent growth. Similarly in magnetizing magnets, after a certain magnetizing force has been reached the subsequent growth due to additional magnetizing force is practically insignificant.

10 By the term "over saturated magnets," we mean some degree approximating complete saturation, but it is to be understood that there are certain points in magnetization of iron and steel which are considered 15 complete saturation, and any forcing of magnetizing force beyond this point is commonly known as "over saturation." For instance, on page 313 of *Wiener's Dynamo Electric Machines*, is given a table of materials and their practical working densities, the practical limit of magnetization and of absolute saturation. The absolute saturation figures are as follows:

25	Wrought iron	130,000
	Cast steel	127,500
	Mitis iron	122,500
	Cast iron containing 6.5% of aluminum	87,500
30	Ordinary cast iron	77,500

Different writers differ as to what this point of absolute saturation is, but this meaning is well understood by those who are familiar with the art.

35 In accordance with the provisions of the patent statutes, we have described the principle of our invention, together with the apparatus which we now consider to represent

the best embodiment thereof; but we desire to have it understood that the apparatus shown is merely illustrative and that the invention can be carried out in other ways.

Having now described our invention, what we claim as new and desire to secure by Letters Patent is:

1. In a railroad signal operated by electromagnetic means, the combination with a movable element of the signal, of an actuating bobbin and a core, a separate demagnetizing coil wound upon the actuating bobbin and connected to the circuit, the said demagnetizing coil being so proportioned that when energized it will relieve the core upon which it is wound of any residuary magnetism which it may contain, and direct mechanical connections between the core and the signal element to move the latter by the direct movement of the former.

2. In a railroad signal operated by electromagnetic means, the combination with a pair of opposed magnets, a plunger connecting the cores of such magnets, signaling means actuated by the movements of the plunger, and a demagnetizing coil for each of said magnets, and connected with a source of electricity for simultaneously energizing a magnet and the demagnetizing coil of the opposed magnet.

This specification signed and witnessed this 27th day of May, 1907.
